ABSTRACT: The disclosure of the invention is a flower-petal holder which comprises a strip of a stiff material, such as a transparent plastic, which is folded across the middle forming opposed covers adapted to engage opposite sides of a petal, a wire stem which passes upwardly through an aperture in the fold of the material, and is hooked over the outer edge of one of said covers, and a fastener, for example, a staple, having the two legs thereof driven through the covers and enclosed petal at opposite sides of the wire stem and then bent over, so that the several elements of the flower and petal holder assembly are secured firmly together.

ATTORNEY.

FLOWER-PETAL HOLDER

The present invention relates to an improved flower-petal holder.

It is an object of the invention to provide an improved flower-petal holder which is of simple construction, and is so shaped as to permit the close assembly of any desired number of flower petals and their holders into compact, lifelike blooms wherein the holders are perfectly concealed.

The flower-petal holder herein disclosed comprises a strip of a stiff material, for example, a clear plastic, folded across the middle to form covers adapted to engage opposite sides of a petal, a wire stem, one end of which is passed upwardly through an aperture in the fold of the material and is hooked over the outer edge of one of the covers, and a fastener, for example, a staple, the two legs of which are driven through the covers and the petal engaged therebetween at opposite sides of the wire, and are then bent over so that the several elements of the assembly are secured firmly together.

The several features of the invention will be readily appreciated from the following description taken in connection with the accompanying drawing, in which:

FIG. 1 is a view in front elevation of the petal holder with a flower petal positioned between the covers and secured by a staple, the two legs of which are driven through the two covers and the included flower petal at opposite sides of the wire;

FIG. 2 is a view in side elevation of the petal holder and petal shown in FIG. 1 looking from the right;

FIG. 3 is a view in front elevation of the petal holder and stem, the leaves being opened out to receive a flower petal; and

FIG. 4 is a view in side elevation of the petal holder and stem as shown in FIG. 3.

The flower-petal holder shown in the drawing as embodying in a preferred form the several features of the invention comprises a strip of a stiff material 10, preferably a clear plastic,

which is folded across the middle to form covers for engagement with opposite faces of a flower petal 12. A wire stem 14 extends upwardly through an aperture 16 through the fold and is hooked over the outer edge of one of the covers. The stem portions forming the two sides of the hook 18 are preferably pressed together providing a frictional contact with the cover which anchors the stem firmly in position. When a flower petal 12 is now inserted between the two covers, as shown in FIGS. 1 and 2, the covers are pressed together, and a staple 20 is driven through the pressed together covers and the included petal, one leg of the staple being located at each side of the stem, so that the elements of the petal holder including the two leaves and the wire stem, and the included petal are firmly secured together as a unit.

15 The petal holder above described provides a support of substantial area for a flower petal which is thus held firmly in a spread out, fully erect position. The holder viewed laterally, however, is only a little thicker than the petal supported thereby, so that petals and their holders may be easily assembled in overlapping relation in any number to form closely packed lifelike blooms of a desired size and shape.

A preferred embodiment of the invention having been described, what I claim is:

1. A flower-petal holder having, in combination, a strip of a stiff material folded across the middle forming covers adapted to engage opposite faces of the petal and having a small aperture through the fold, a wire stem extending through said aperture and having an end thereof hooked over the outer edge of one of said covers, and a fastener adapted to be driven through the covers and included petal for securing the covers, included petal and wire stem firmly together.

2. A flower-petal holder according to claim 1, in which said fastener is a staple having two legs adapted to be driven through said covers and included petal at opposite sides of said wire stem, and doubled under.

3. A flower-petal holder according to claim 2, in which said strip of stiff material is a clear plastic.
